METHOD OF MAKING DIES

George R. Meyercord, Chicago, Ill., assignor, by
mesne assignments, to Reconstruction Finance
Corporation, a Federal corporation

Application May 27, 1933, Serial No. 673,175

16 Claims. (Cl. 76—107)

Forming dies as, for example, dies to form or mold plywood sheets or panels and leave them with smooth surfaces that require no subsequent sanding or similar treatment, are very costly when the dies are made by hand as has heretofore been the practice. The object of the present invention is to make it possible to produce such dies at a very low cost.

In carrying out my invention I make rudimentary die members in the form of rough castings of the proper shape and then sheathe the die face surface with polished metal, such as steel, in a manner that is simple and effective and insures perfect configuration of the die faces and perfect registration. By proceeding in this way, instead of being required to cut away the solid metal of a block and painstakingly finishing the same to produce a die face, I need only fashion a properly shaped pattern of wood or other material that can be easily worked.

After the complementary rudimentary die blocks have been cast, they are forced together under heavy pressure with elements interposed between the same to complete the dies. These elements comprise polished sheets of hard, ductile metal that are to serve as the actual die faces in the completed dies, together with sheets of soft metal, such as lead, interposed between the sheets of harder metal and the castings. There must be at least two of the sheets of steel or other hard metal, and there should also be between these two sheets a panel of the same thickness as the wood or other material which is to be formed by the dies. Preferably this interposed panel consists of thin sheets of steel or other hard, ductile metal. When the dies are closed, all of the sheets are deformed; the soft sheets of lead or the like being brought into intimate contact with all portions of the rough die faces in the castings, while the adjacent sheets of steel or the like follow the contours of these die faces and the additional group of sheets are pressed into the shape that will afterwards be taken by the product to be produced in the dies. The lead or other soft material serves to fill up all of the pits in the die faces of the castings and to insure an equalized distribution of pressure upon the hard metal sheets in contact therewith, so that these latter sheets conform closely to the contour of the corresponding die faces without, however, being influenced by the surface roughness of the rudimentary die faces.

When the die blocks are separated, following the operation just described, all of the hard

metal sheets except the two that constitute the working faces of the two dies are removed and the two remaining deformed sheets are welded at their edges to their respective blocks, or are otherwise permanently secured so that they will not accidentally become loose, and the dies are ready for use.

In some cases I prefer to apply the pressure in effecting the facing of the die blocks through a cushion. Thus I may place above the upper die block and underneath the lower die block sheets of lead or the like which will permit the blocks to adjust themselves bodily as the pressure is applied, and thus insure perfect nesting or registration of the working faces. When lead pads are placed above and below the die blocks, these pads are preferably protected by sheets of steel lying, respectively, underneath the lower pad and on top of the upper pad. When the step of pressing the assembly has been completed, the steel sheets that protect the pads underneath and above the die blocks may be welded or otherwise fastened at their edges or margins to their respective blocks.

My invention may be applied to advantage in the manufacture of very long dies which it would otherwise be very difficult to make and for which it might be difficult to make patterns that would not warp. In the case of extremely long dies, I propose to make two short patterns, one for each die member, and cast a sufficient number of blocks to provide the desired length of die when the blocks are placed end to end. The process of completing the long die is then the same as that which I have just described; it being understood that the various sheets that are placed between and above and below the rudimentary die members extend continuously from one end of the die to the other and therefore serve to tie together the plurality of blocks or sections of which each die is constructed.

The various features of novelty whereby my invention is characterized will hereinafter be pointed out with particularity in the claims; but, for a full understanding of my invention and of its objects and advantages, reference may be had to the following detailed description taken in connection with the accompanying drawings, wherein:

Figure 1 is a view, partly in elevation and partly in section, showing two complementary rudimentary die blocks in a press, together with the various sheet metal elements above, below and between the blocks, preparatory to closing the press and completing the dies, the view showing the

plates or sheets that lie between the blocks in exploded condition; Fig. 2 is a section, on a larger scale, showing the condition after the press has been closed under heavy pressure; Fig. 3 is a view, 5 similar to Fig. 2, showing the completed dies closed on a piece of work; Fig. 4 is a view, partly in elevation and partly in section, showing a dish adapted to be formed by the dies of Fig. 3; Fig. 5 is a transverse section through an elongated die, 10 showing it closed on the work; Fig. 6 is a side view, on a much smaller scale, showing the die of Fig. 5, together with the press; and Fig. 7 is a perspective view of a piece of molding which is 15 the product of the die shown in Figs. 5 and 6.

15 Referring to Figs. 1-4 of the drawings, 1 and 2 are cast metal blocks having the form of having die faces of such shape as to cause them to deform a panel on which they close and give it the shape of the dish A shown in Fig. 4. These blocks are 20 as accurate in contour as ordinary castings may be, but are not suitable for use in their natural condition because of the roughness of the surfaces thereof. It will be seen that easily made wood or other patterns are all that are required 25 to make it possible to cast these blocks.

In carrying out my invention in the preferred way, I set the block 1 upon the bed or lower platen B of a press, first laying on the bed or platen a thin sheet 3 of steel upon which, in turn, 30 is laid a sheet 4 of lead or other soft metal. On top of this die block 1 I lay a thin sheet 5 of lead or other soft metal and, on top of that, I place a polished sheet 6 of hard, ductile steel or other suitable metal. These four sheets are to form a 35 permanent part of the completed die. On top of the plates or sheets 5 and 6 I lay a little group of thin plates or sheets 7 the combined thickness of which is equal to the thickness of the material of the finished plate-like product A. Then, upon 40 the sheets or plates 7 I lay a sheet 8, similar to the sheet 6, followed by a sheet 9 similar to the sheet 5. The upper block 2 is placed on top of the little stack of sheets resting on the lower block and, on top of the upper die block, are 45 placed a sheet 10, similar to the sheet 4, and then a sheet 11, similar to the sheet 3. When the press is closed, the upper platen C first is brought down into engagement with the sheet 11 and then presses the upper die block down. Since the completed die is to produce a dish-like product, the die face of the lower die member contains a concavity or depression 12, while the die face of the upper die member is provided with a projecting boss 13 complementary to the concavity or recess 50 in the other member. Therefore, when the press is closed and sufficient pressure is applied, the stack of sheets 5-9, inclusive, will be deformed so as to take the shapes of a series of dishes nested one within the other, as shown in Fig. 2. The 55 soft lead sheets 5 and 9 are also deformed otherwise, so as to fill all of the pits and depressions in the faces of the castings and prevent the adjacent hard metal plates 6 and 8 from being affected by the surface roughness of the castings. Consequently, if the sheets 6 and 8 are polished at the 60 time the assembly is put in the press, the surfaces thereof will remain smooth and polished during the pressing operation and, when the press is opened, the die blocks are separated, and the little 65 stack 7 of sheets is removed, each die block will remain faced with a thin layer of lead or the like overlaid with smooth, hard, polished sheet material.

The soft sheets 4 and 11 permit the die blocks 70 to shift bodily to a small degree in the event that

one or the other block requires to tilt or otherwise shift a little in order to permit accurate nesting of the two die faces.

At any time after the press has been closed on the assembly of cast metal blocks and sheet material, as indicated in Fig. 2, the edges or marginal portions of the sheets 3, 6, 8 and 10 are welded or otherwise permanently fastened to the corresponding die blocks; whereby each die consists of a casting, two hard metal sheets and two soft metal sheets, all united into an integral structure. In Fig. 3 I have shown the hard metal sheets secured by welding, as indicated at 14.

In Fig. 7 there is illustrated a molding D consisting of a strip of plywood that has been shaped in forming dies. It is evident that such a product may be required to be manufactured in lengths many feet long and ordinary dies for forming it are very expensive. A set of dies may be made quite cheaply in accordance with my invention. Instead, however, of making patterns the full length of the dies, I make only short patterns; casting therefrom blocks which are then placed end to end to give the desired length of die. Thus, in Figs. 5 and 6 one die contains a 25 considerable number of blocks 21 placed end to end, while the complementary die member contains a plurality of blocks 22. The blocks of one set are preferably longer than those of the other so that joints will be staggered, as shown. The 30 strips that are associated with the die blocks in building up an assembly to be squeezed in a power press are the same in number, character and disposition as in the case of the other dies, and they are as long as the die instead of being in short 35 lengths as are the die blocks. In Figs. 5 and 6 strips 23-26, inclusive, and 28-31, inclusive, correspond to the strips 3-6, inclusive, and 8-11, inclusive, in Figs. 1-3. The group of temporary 40 filler strips corresponding to the strip 7 have not been shown, since the steps that bring about the condition illustrated in Fig. 5 are precisely the same as those illustrated in Figs. 1 and 2. In Fig. 5 the strips are shown as having been welded to the blocks at their edges.

Obviously the strips tie together the blocks of each group or set into a single rigid die member.

While I have illustrated and described with particularity the preferred method of building up only two kinds of dies, I do not wish to be limited to the details thus illustrated and described; but intend to cover every method and form of die coming within the definition of my invention constituting the appended claims.

I claim:

1. The method of producing working face plates for complementary forming dies, which comprises the casting of rough complementary metal blocks of the proper shape, and forcing said blocks together under heavy pressure while having between their die faces a stack of sheets comprising upper and lower sheets of soft metal, such as lead, and intermediate sheets including sheets of hard ductile metal in contact with the lead sheets.

2. The method of producing working face plates for complementary forming dies, which comprises the casting of rough complementary metal blocks of the proper shape, and forcing said blocks together under heavy pressure while having between their die faces a stack of sheets comprising upper and lower sheets of soft metal, such as lead, and more than two intermediate sheets of hard ductile steel.

3. The method of producing working face

- plates for complementary forming dies, which comprises the casting of rough complementary metal blocks of the proper shape, and forcing said blocks together under heavy pressure while having between their die faces a stack of sheets consisting of upper and lower sheets of soft metal, such as lead, and intermediate sheets consisting of a group the combined thicknesses of which is equal to the thickness of the panels to be worked in the dies lying between their die faces a stack of sheets consisting of upper and lower sheets of soft metal, such as lead, and intermediate sheets consisting of a group the combined thicknesses of which is equal to the thickness of the panels to be worked in the dies lying between their die faces a stack of sheets of hard ductile metal that are to form the faces of the dies, and fastening each of said sheets of hard ductile metal to the corresponding block. 5
10. The method of producing complementary forming dies, which comprises the casting of rough complementary metal blocks of the proper shape, forcing said blocks together under heavy pressure while having between their die faces a stack of sheets consisting of upper and lower sheets of soft metal, such as lead, and intermediate sheets consisting of a group the combined thicknesses of which is equal to the thickness of the panels to be worked in the dies lying between their die faces a stack of sheets comprising upper and lower sheets of soft metal, such as lead, and intermediate sheets of hard ductile metal spaced apart by interposed sheet material. 15
15. The method of producing working face plates for complementary forming dies, which comprises the casting of rough complementary metal blocks of the proper shape, and forcing said blocks together under heavy pressure while having between their die faces a stack of sheets comprising upper and lower sheets of soft metal, such as lead, and intermediate sheets of hard ductile metal held apart by spacing material, and then welding together each block and the edges of the nearest sheet of hard metal. 20
20. The method of producing working face plates for elongated complementary forming dies which consists in casting two sets of rough metal blocks of the proper shapes to cause the blocks of one set to produce one of the die members in rudimentary form when placed end to end and the blocks of the other set to produce in rudimentary form the other die when they are placed end to end, forcing the dies in such rudimentary forms together under heavy pressure while having between their die faces a stack of sheets as long as the die and comprising upper and lower sheets of soft metal, such as lead, and an intermediate layer containing two sheets of hard ductile metal engaged respectively with the said upper and lower sheets of soft metal. 25
25. The method of producing working face plates for a forming die which consists in casting a rough metal block of the proper shape, placing against the die face of such block a sheet of soft metal, such as lead, and an overlying sheet of hard ductile metal, and applying pressure to mold said sheets into intimate engagement with said die face. 30
30. The method of producing a forming die which consists in casting a rough metal block of the proper shape, placing against the die face of such block a sheet of soft metal, such as lead, and an overlying sheet of hard ductile metal, applying pressure to mold said sheets into intimate engagement with said die face, and then fastening said sheet of hard ductile metal to said block. 35
35. The method of producing a forming die which consists in casting a rough metal block of the proper shape, placing against the die face of such block a sheet of soft metal, such as lead, and an overlying sheet of hard ductile metal, applying pressure to mold said sheets into intimate engagement with said die face, and then fastening said sheet of hard ductile metal to said block. 40
40. The method of producing a forming die which consists in casting a rough metal block of the proper shape, placing against the die face of such block a sheet of soft metal, such as lead, and an overlying sheet of hard ductile metal, applying pressure to mold said sheets into intimate engagement with said die face, and then welding the edge portions of said sheet of hard ductile metal to said block. 45
45. The method of producing working face plates for dies, which comprises the casting of rough complementary metal blocks of the proper shapes, interposing between the blocks a stack of sheets, including sheets whose combined thickness equals the thickness of the panels to be worked in the dies lying between a pair of smooth hard ductile sheets, and forcing the blocks together under heavy pressure. 50
50. The method of producing working face plates for dies, which comprises the casting of rough complementary metal blocks of the proper shapes, interposing between the blocks a stack of sheets, including sheets whose combined thickness equals the thickness of the panels to be worked in the dies lying between a pair of smooth hard ductile sheets, and forcing the blocks together under heavy pressure. 55
55. The method of producing working face plates for dies, which comprises the casting of rough complementary metal blocks of the proper shapes, interposing between the blocks a stack of sheets, including sheets whose combined thickness equals the thickness of the panels to be worked in the dies lying between a pair of smooth hard ductile sheets, and forcing the blocks together under heavy pressure. 60
60. The method of producing working face plates for dies, which comprises the casting of rough complementary metal blocks of the proper shapes, interposing between the blocks a stack of sheets, including sheets whose combined thickness equals the thickness of the panels to be worked in the dies lying between a pair of smooth hard ductile sheets, and forcing the blocks together under heavy pressure. 65
65. The method of producing working face plates for dies, which comprises the casting of rough complementary metal blocks of the proper shapes, interposing between the blocks a stack of sheets, including sheets whose combined thickness equals the thickness of the panels to be worked in the dies lying between a pair of smooth hard ductile sheets, and forcing the blocks together under heavy pressure. 70
70. The method of producing working face plates for dies, which comprises the casting of rough complementary metal blocks of the proper shapes, interposing between the blocks a stack of sheets, including sheets whose combined thickness equals the thickness of the panels to be worked in the dies lying between a pair of smooth hard ductile sheets, and forcing the blocks together under heavy pressure. 75

plates for dies which consists in casting two sets of blocks of the proper shapes to cause the blocks of one set to form a rudimentary die member when placed end to end, and the blocks of the other set to form a complementary rudimentary die member when placed end to end, interposing between said sets of blocks, while the blocks in

each are arranged end to end, a stack of long sheets including sheets whose combined thickness equals the thickness of the panels to be worked in the dies lying between a pair of smooth ductile hard sheets, and forcing the two sets of blocks together under heavy pressure.

GEORGE R. MEYERCORD.
